Attorney

UNITED STATES PATENT OFFICE.

DAVID BARATZ AND HARRY MILLER, OF PROVIDENCE, RHODE ISLAND.

CAP.

Application filed February 23, 1923. Serial No. 621,938.

To all whom it may concern:

Be it known that we, DAVID BARATZ and HARRY MILLER, citizens of the United States, residing at Providence, in the county 5 of Providence and State of Rhode Island, have invented new and useful Improvements in Caps, of which the following is a specification.

This invention relates to certain new and 10 useful improvements in caps, and the primary object thereof is to provide novel means for enabling the head engaging band to be easily and quickly adjusted so as to vary the diameter thereof, and consequently 15 permit fitting of the cap to heads of different sizes.

A further object of the invention is to provide means for the purpose mentioned which acts to resiliently hold the cap onto 20 the head to thereby afford a protection against the cap blowing off the head of the user.

The invention still further aims to provide adjusting means for the head band 25 which can not only be easily and quickly adjusted, but which also effectively maintains the adjustment, once the latter has been made.

The invention still further aims to provide adjusting means which can be easily 30 and economically produced and which also does not in any way interfere with the comfortable use or wear of the cap.

The invention has still further and other 35 objects which will be later set forth and manifested in the course of the following description.

In the drawings:

Figure 1, is a bottom plan view of a cap 40 made in accordance with the present invention;

Figure 2, is an enlarged section on line 2—2 of Figure 1, and

Figure 3, is a similar view on line 3—3 of 45 Fig. 1.

In proceeding in accordance with the present invention, the head band 1, of the cap is formed hollow throughout, or tubular and is stitched along lines extending 50 circumferentially thereof, as indicated at 2 and 3, the lines of stitching being spaced to afford a pocket 5, in which the elastic strip 4 is housed. One end 6 of the elastic strip 4, has a series of spaced female members 7, of snap fastenings secured thereto, the female members being also secured to

the inner wall 2^A of the head band and being exposed through the latter, as illustrated in Figures 1 and 2 of the drawings. The opposite end 8 of the elastic strip 4 50 carries the male member 9 of a snap fastening, which male member is engageable with a selected one of the female members 7. The part of the pocket 5, adjacent to the female members 7, of the snap fastenings 55 is open as indicated at 9^A so as to permit the end 8, of the elastic to project therethrough and to have its male member engage a selected one of the female members of the snap fastenings. The female members 7, function in a dual manner, namely as such and also to secure one end of the elastic strip to the head band and in the pocket thereof. For the purpose of affording comfortable wear to the user, a sweat 70 band 11, is employed which overlies the end 8, of the elastic strip and all of the snap fastenings, and conceals the latter as well as serving as a means of affording comfort, by preventing contact of the aforementioned parts with the head of the wearer.

In use, it will be seen, that to adjust the cap, it is merely necessary to raise the sweat band, to expose the fastenings and more 85 especially to expose the end 8, with the male fastening member, whereupon the elastic is drawn or moved to the desired point, or until the head band is found to afford the required or desired fit, whereupon the male 90 member 9 and a selected one of the female fastenings are snapped into engagement. Obviously, any number of the female fasteners may be employed as desired, in order to afford any necessary or desirable range 95 of adjustment. It will now be seen that the elastic affords a resilient medium for tensioning the head band, so that by drawing same fairly tight, the cap can be adjusted so as to resist displacement by the 100 wind, or other forces such as is desirable in playing games of various sorts.

Having thus described our invention, what we claim as new and desire to secure by Letters Patent is:—

1. In a cap, a tubular head band forming a pocket extending throughout the circumference of the cap and having an opening, an elastic strip in the pocket having one end thereof free and extending in the opening, a member of a snap fastener on said free end of the strip, a series of comple-

2
mentary snap-fastening members secured to the opposite end of the elastic and to the head band and extending in the opening for selective engagement with said first 5 named snap fastening member, and a sweat band carried by the cap and movable over and away from said opening so as to cover and expose said snap fastening members.

2. In a cap, a tubular head band forming 10 a pocket extending throughout the circumference of the cap and having an opening, an elastic strip in the pocket having one end thereof free and extending in the opening, a member of a snap fastener on said

free end of the strip, and a series of complementary snap-fastening members secured to the opposite end of the elastic and to the head band and extending in the opening for selective engagement with said first 15 named snap fastening member. 20

In testimony whereof we have signed our names to this specification in the presence of two subscribing witnesses.

DAVID BARATZ.
HARRY MILLER.
